UNITED STATES PATENT OFFICE

168,331

SEWING MACHINE

Heinrich Bungert, Kaiserslautern, Germany, assignor to G. M. Pfaff A. G., Kaiserslautern, Germany

Application October 31, 1951, Serial No. 17,196

Term of patent 14 years

(Cl. D70—1)

To all whom it may concern:

Be it known that I, Heinrich Bungert, a citizen of Germany, residing at the city of Kaiserslautern, State of Germany, have invented a new, original, and ornamental Design for a Sewing Machine, of which the following is a specification, reference being had to the accompanying drawing, forming a part thereof.

In the drawing:

Figure 1 is a side view of a sewing machine embodying my new design with the working table in a lowered position;

Figure 2 is a front view thereof;

Figure 3 is a rear view thereof;

Figure 4 is a side view opposite Figure 1 having the working table in a raised position; and

Figure 5 is a top plan view of the sewing machine.

I claim:

The ornamental design for a sewing machine, substantially as shown and described.

HEINRICH BUNGERT.
